Des. 212,101
Patented Aug. 27, 1968

212,101

ROLL PAPER DISPENSER

Robert E. Watson, 31750 Coronet Drive,
Farmington, Mich. 48024

Substituted for abandoned design application Ser. No.
4,111, Sept. 30, 1966. This application Sept. 25, 1967,
Ser. No. 8,725

Term of patent 14 years

(Cl. D33—31)

FIG. 1

FIG. 2

FIG. 3

FIG. 4

FIGURE 1 is a side elevational view of a roll paper dispenser showing my new design;

FIGURE 2 is a front elevational view thereof;

FIGURE 3 is a bottom plan view thereof; and

FIGURE 4 is a front perspective view thereof in an open position, the rear being substantially plain.

I claim:

The ornamental design for a roll paper dispenser, as shown and described.
